UNITED STATES PATENT OFFICE.

CHARLES HENRY AUGUSTUS FREDERICK LOCKHART ROSS, OF BALNAGOWN CASTLE,
COUNTY OF ROSS, SCOTLAND.

FIREARM.

1,021,706.

Specification of Letters Patent. Patented Mar. 26, 1912.

Application filed July 27, 1911. Serial No. 640,942.

To all whom it may concern:

Be it known that I, CHARLES HENRY AUGUSTUS FREDERICK LOCKHART ROSS, a subject of the King of Great Britain, residing at Balnagown Castle, Rossshire, Scotland, have invented certain new and useful Improvements in Firearms; and I do hereby declare the following to be a full, clear, and exact description of the invention, such as will enable others skilled in the art to which it appertains to make and use the same.

This invention relates to fire arms and has for its object the production of a rifle which will be certain in action, simple in construction and less expensive to manufacture than similar arms heretofore proposed.

To these ends the invention consists in the details of construction and combinations of parts more fully hereinafter disclosed and particularly pointed out in the claims.

Referring to the accompanying drawings forming a part of this specification in which like numerals designate like parts in all the views:—Figure 1 is a side elevational view 25 of a rifle made in accordance with my invention and showing the operating parts in dotted lines; Fig. 2 is a view similar to Fig. 1, but showing some of the parts in section; Fig. 3 is a partly sectional view showing the 30 parts in their after firing positions; Fig. 4 is a side elevational view of the breech bolt; Figs. 5 and 6 are respectively a bottom plan view and an enlarged end view of the breech bolt; Fig. 7 is an enlarged sectional 35 view of the forward end of the breech bolt and extractor, taken on the line 7—7, Fig. 6; Fig. 8 is a side elevational view of the firing plunger; Fig. 9 is a plan view of the receiver; Figs. 10, 11 and 12 are cross sectional views taken respectively on the lines 40 10—10, 11—11, and 12—12 of Fig. 3; Fig. 13 is a sectional view taken on the line 13—13 of Fig. 3; and Fig. 14 is a detail sectional view of the rear end of the receiver.

45 1 indicates the stock, 2 the barrel, 3 the receiver, 4 the sight, 5 the trigger, and 6 the trigger guard. The breech bolt 7 is provided with an enlarged hollow extension 8 into which fits the hollow firing plunger 9 having a slot 10 through which said extension passes the pin 11 as shown. Fitting the interior of the plunger 9 and resting against the pin 11 is the firing spring 12, and carried by said plunger and preferably

rigid therewith is the sear lug 13 having 55 the shoulder 14.

The breech bolt 7 is slotted at 15, 16 and 17 as shown in Fig. 6. In the slot 15 fits the extractor 18 pivoted at 19 and having the spring extension 20.

60 In the slot 16 fits the firing pin 21 whose head 22 extends into the breech bolt extension 8 and is adapted to be struck by the firing plunger 9 as indicated in Fig. 3. The slot 17 accommodates the ejector 25, and the receiver 3 is provided with an annular shoulder 26 against which the enlarged rear end of the breech bolt may take when in its forward position.

65 The breech bolt extension 8 is provided on its bottom with a lug 28 and a slot 29 through which the sear lug 13 plays. Pivoted at 30 is a holding dog 31 provided with a finger piece 32 adjacent the trigger 5, and with detent 33 having an inclined surface 70 34 contacting with the lug 28. The surface 34 may be made of the proper inclination to permit the breech bolt to be blown back upon the explosion of the cartridge, or it may be made so steep as to require the bolt 75 to be manually unlocked after each discharge, as will appear below. Pivoted on the pin 30 is also a sear lever 35, whose upper end 36 rests against the locking dog or lever 31 and whose lower end 37 is normally pressed away from said dog by the spring 38. The said sear lever 35 is also provided with a sear nose 40 adapted to engage the shoulder 14 on the lug 13 as shown. The lower side of the receiver 3 80 is provided with a slot 41 to accommodate the parts, and the sear lever is provided with a pin 42 against which takes a spring 43 secured at 44 to the receiver. Pivoted on the pin 42 is the trigger 5 provided with 85 the fulcrum or lug 46 adapted to normally rest against the receiver as shown. In order to more firmly hold the said fulcrum in place the spring 43 is provided with a tongue 48 which takes under said lug 46, 90 100 thereby constituting a yielding pivot for the trigger.

95 The receiver 3 is provided with a slot 50 in which the operating handle 51 plays, and the rear end of said receiver may be closed 105 by a cap 52 provided with a latch 53, controlled by a spring 54 and pivoted at 55. The forward end 56 of said latch, after the

cap is screwed in place, snaps into said slot 50 and securely holds the cap 52 in place. Said cap may also be provided with a sight 57 provided with the spring 58 and controlled by the adjusting nut 59 mounted on the pin 60.

The operation of my improved firing mechanism is as follows:—The breech bolt and firing plunger is moved to the rear by 10 means of the handle 51, whereupon a cartridge is inserted through the opening 65 in the receiver, and pushed into firing position by a reverse movement of the handle 51 and bolt 7. Upon moving the bolt forward, 15 however, the shoulder 14 on the lug 13 which previously occupied a position in the rear of the sear nose 40, now catches on said nose, prevents the firing plunger 9 from moving forward with the bolt, and at the same time 20 causes the spring 12 to be placed under compression, thereby cocking the piece. Also when the bolt 7 is in its firing position the detent 33 takes up its locking position under the action of the spring, and if its face 34 25 is sufficiently abrupt, said detent firmly holds said bolt against recoil upon firing, otherwise the force of explosion blows the bolt back without requiring the aid of the handle 51. The piece being cocked as described, a pull on the trigger disengages the 30 sear nose from the shoulder 14 and the firing plunger moves forward under the action of the spring 12 and strikes the firing pin head 22, which causes the firing pin 21 to 35 explode the cartridge. If the gun is wholly operated manually; the locking dog 31 is now swung on its pivot by pressing the end 32 with the finger, and the detent 33 is disengaged from the shoulder 28, whereupon 40 the bolt is manually retracted by means of the handle 51, the cartridge shell ejected by coming in contact with the ejector 25, a new cartridge inserted through the opening 65, and the piece recocked in the manner above 45 disclosed. On the other hand if the gun is not to be entirely operated manually, but is to be partially automatic, the inclined surface 34 is so chosen as to permit the bolt to be blown back and the cartridge extracted by 50 the force of the explosion. A new cartridge is then inserted in any suitable manner, and the bolt returned in order to recock the piece. Should it be desired to carry the gun loaded but not cocked the parts may be brought into 55 the positions shown in Fig. 3.

It is obvious that those skilled in the art may vary the arrangement of parts and details of construction without departing from the spirit of my invention, and therefore I 60 do not wish to be limited to such features except as may be required by the claims.

What I claim is:—

1. In a fire arm the combination of a breech bolt provided with an extension; a 65 firing pin carried by said bolt; a shoulder

carried by said extension; a detent adapted to engage said shoulder; a firing means independent of said pin carried by said extension; a shoulder carried by said firing means; a sear coacting with said last mentioned shoulder; a trigger controlling said sear; and means independent of said trigger for moving said detent out of engagement with said shoulder, substantially as described.

2. In a fire arm the combination of a breech bolt provided with an extension; a firing pin carried by said bolt; a shoulder carried by said extension; a detent adapted to engage said shoulder; a firing means independent of said pin carried by said extension; a shoulder carried by said firing means; a hand operated lever controlling said detent; a sear coacting with said last mentioned shoulder; and a trigger controlling said sear, substantially as described.

3. In a fire arm the combination of a breech bolt provided with an extension; a firing pin carried by said bolt; a shoulder carried by said extension; a detent provided with a finger piece and adapted to engage said shoulder; a firing means independent of said pin carried by said extension; a shoulder carried by said firing means; a spring controlled lever coacting with said detent and provided with a sear coacting with said last mentioned shoulder; and a trigger independent of said lever for controlling said sear, substantially as described.

4. In a fire arm the combination of a breech bolt provided with a slot and having a hollow slotted extension; an ejector located in the slot of the breech bolt; a firing plunger located in the hollow extension and having a sear lug provided with a shoulder extending through the slot of said extension; a detent adapted to retard the rearward movement of said bolt; a sear coacting with said shoulder; and a trigger pivoted to said sear; substantially as described.

5. In a fire arm the combination of a breech bolt provided with a slot and having a hollow slotted extension; an ejector located in the slot of the breech bolt; a firing plunger located in the hollow extension and having a sear lug provided with a shoulder extending through the slot of said extension; a detent adapted to retard the rearward movement of said bolt; a sear pivoted concentrically with said detent coacting with said shoulder; and a spring controlled trigger pivoted to said sear; substantially as described.

6. In a fire arm the combination of a breech bolt provided with a slot and having a hollow slotted extension; an ejector located in the slot of the breech bolt; a firing plunger provided with a spring located in the hollow extension and having a sear lug provided with a shoulder extending through

the slot of said extension; a pivoted detent adapted to retard the rearward movement of said bolt; means for manually operating said detent; a sear coacting with said shoulder; and a trigger pivoted to said sear; substantially as described.

7. In a fire arm the combination of a breech bolt having a slotted extension provided with a shoulder; a pivoted detent engaging said shoulder and provided with a finger piece; a firing plunger carried by said extension having a sear lug extending through the slot thereof; a pivoted sear lever coacting with said detent and lug; and a spring controlled trigger pivoted to said sear lever; substantially as described.

8. In a fire arm the combination of a slotted breech bolt having a slotted extension provided with a shoulder; a firing pin located in the slot of said breech bolt and extending into said extension; a pivoted detent engaging said shoulder and provided with a finger piece; a flaring plunger carried by said extension having a sear lug extending through the slot thereof and adapted to strike said firing pin; a pivoted sear lever coacting with said detent and lug; and a spring controlled trigger pivoted to said sear lever; substantially as described.

9. In a fire arm the combination of a breech bolt having a plurality of slots; an extractor located in one of said slots; a firing pin located in another of said slots; an ejector located in a third slot; a slotted hollow extension rigid with said bolt; a hollow firing plunger located in said extension; a firing spring located in said hollow plunger; a lug carried by said extension; a detent coacting with said lug; a sear lug carried by said plunger and a sear and trigger pivoted together coacting with said sear lug; substantially as described.

10. In a fire arm the combination of a fir-

ing plunger; a sear lug carried by said plunger; a pivoted sear lever coacting with said lug; a trigger provided with a fulcrum pivoted to said lever; and a two part spring one portion of which bears on the pivot between said lever and trigger, while the other portion bears on said fulcrum; substantially as described.

11. In a fire arm the combination of a slotted receiver provided with a reduced front and an enlarged rear bore; an operating handle reciprocating in the slot of said receiver; a screw threaded connection for the barrel carried by the front end of said receiver; a screw threaded cap closing the rear end of said receiver; an ejector passing through the walls of said receiver and projecting into said reduced bore; and a latch adapted to enter said slot for holding said cap in place, substantially as described.

12. In a fire arm the combination of a slotted receiver provided with reduced and enlarged bores; an ejector passing through the walls of the receiver and extending into said reduced bore; said receiver also provided with a shoulder against which the breech bolt is adapted to take at the junction of said reduced and enlarged bores; an operating handle reciprocating in the slot of said receiver; a screw threaded cap closing the end of said receiver; an adjustable sight carried by said cap; and a spring controlled latch adapted to enter said slot for holding said cap in place, substantially as described.

In testimony whereof, I affix my signature in presence of two witnesses.
